UNITED STATES PATENT OFFICE

2,537,135

TRANSPARENT BINDER FOR LOOSE
LEAVES AND THE LIKE

William Hempel, Fair Lawn, N. J.

Application November 18, 1949, Serial No. 128,051

7 Claims. (Cl. 281—29)

1

This invention relates to binders or covers for books, magazines, or the like, and particularly for loose leaf books and records, and has for its main object to provide a device of the type indicated which will be of improved construction, operation, and use over those heretofore proposed for such purpose.

Another object of this invention is to provide a device as characterized hereinbefore, having a transparent top sheet through which the contents are displayed, may be observed, or read, but the securing means and construction of the back for the book, loose leaves and the like, will be concealed thereby providing my device with a desired feature at the same time making it of aesthetic appeal.

Still another object of my invention is to provide a device of this type which will have an opaque rear or bottom sheet, flexible at least at its inner margin, the back of the binder being formed from said flexible portion of the rear including a novel, simple, efficient means to secure said transparent top thereto and providing said concealing means for the inner construction of the device and its securing means.

Further objects of this invention will be apparent as the specification of the same proceeds or will be pointed out therein.

In the drawings forming a part of this specification and accompanying the same:

Fig. 1 is a plan view of a preferred embodiment of my invention, and

Fig. 2 is a sectional view thereof, on a larger scale, the section being taken on the line 2—2 of Fig. 1;

Fig. 3 is a sectional fragmentary and diagrammatic view of a modification, and

Fig. 4 is a similar view of another modification.

Referring now to the drawings more in detail by characters of reference, the numeral 10 indicates the preferred embodiment of my invention, in general, being a cover or binder for loose leaf books or other similar articles.

It is composed of two main elements, an opaque, preferably flexible, rear member or cover sheet 11, and a front or top transparent cover or sheet 12.

In the preferred embodiment shown in Figs. 1 and 2 the rear sheet 11 is continued at its inner end in several folds, generally indicated by the numeral 13, which jointly with appropriate portions of the transparent top 12 and other parts and connecting devices will form the back of the binder or book cover 10.

The preferred arrangement of the folds 13 in

the back of the device will be formed by first an upwardly turned portion or fold 14, then a downward one 15, the two having the bend 16 between them. The material of the rear sheet 11 then is continued in an upward bend 17 and an upward innermost fold 18 whereupon the same is turned horizontally forming a top flange 19. The top sheet 12 of my device preferably will be made of flexible but resilient transparent material, like an appropriate plastic, many of which are well known in this art.

The inner marginal end thereof will be turned downwardly into a fold 20 which will be inserted between the two inner fold members 15 and 18 of the rear sheet 11, after which all the mentioned folds and the downwardly turned marginal inner end 20 of the top sheet will be secured together by any appropriate means.

It will be seen that in this simple manner I will provide a cover or binder for books and the like which will have a transparent top wherethrough the top page of the book, or loose leaves, or the like, inserted into my novel binder and cover will be shown, may be observed, or read to great advantage and convenience, at the same time being novel and attractive.

However, all the mechanism and possibly securing means at the back 13 of the book, or other article within my binder or cover, will be concealed by the opaque forward top flange 19 of the rear sheet.

In the preferred embodiment of Figs. 1 and 2, I show my binder or cover as employed for loose leaves and I indicate at 21 the loose leaf pages threaded on a ring 22, which, as usual in such devices, may be open and further pages threaded on it or removed therefrom as is well known in this art.

The various parts of the back 13 may be secured together as has been mentioned by any appropriate means, in the embodiment shown rivets 23 being indicated for this purpose which also may be used to secure the loose leaf rings and their usual base 24 on the back 13 of the binder or cover.

In Fig. 3 I show a modification of my device in which the rear cover here also indicated by the numeral 11 will simply have an upward bend 26 at its inner end 25 continued in a forward covering flange 27 similarly arranged and for the same purpose as the opaque flange 19 was indicated in the preferred embodiment of Figs. 1 and 2.

The transparent top 12 here also will have a downward rear margin 28 simply folded or flat-

tened on the upward bend or fold 26 in the opaque rear cover, and a specifically prepared back 28 will be secured over the parts 26 and 20 by any appropriate means, as it is well known in the bookbinding art, the back 28 preferably being in the form of a curved solid rigid strip or bar as usual.

In Fig. 4 another modification of my device is indicated wherein the opaque rear cover 11 is continued in similar bends or folds 14, 15 and 18 as has been described in the preferred modification of Fig. 1 and is terminated by the concealing upper flange 19. The transparent top 12 again will have a similar downward bend or fold 20 and the mentioned bends or folds of the rear cover, and the downward flange 20 of the transparent top, will be secured together by any appropriate means, and in this manner a simple but stiff back will be formed for my cover or binder for a book, or any other appropriate object, wherein the inner margin of the book or other article with its possible securing means will be concealed while the top of the cover or binder will be transparent.

One element in said securing means may consist in a row of stitches 29 between the upper ends of the two inner folds 15 and 18 of the opaque rear sheet 11 passing through the upper end of the downward flange 20 of the transparent top 12 and in this manner securing the parts together with means which will be invisible to the outside, the outermost field 14 of the rear cover being then secured thereon by any appropriate means if desired.

It is to be understood that such concealed securing stitches may be employed at the top of the back of other modifications of my invention, as they are indicated at 29 in Fig. 2.

Also, if desired, my device may be made without the concealing flange or flap 19, the top of the same then having a clear attractive transparent appearance, particularly if the inner mechanism observable therethrough is attractive, like gold plated rings and the like.

What I claim as new and want to protect by 45 Letters Patent of the United States, is:

1. A binder or cover for books, magazines, loose leaf sheets and the like, comprising, in combination, a rear sheet having a flexible inner marginal portion, upwardly standing folds formed from said inner margin thereof, offering an upward opening therebetween, a final lateral

narrow flange at the upper end of the innermost fold, a top sheet for the device, the inner marginal portion thereof being folded downwardly and inserted into said upward opening in the folds of the rear sheet, and means to secure together the vertical folds thus formed of the rear and the top thereby forming the back of the device.

2. In a device, as set forth in claim 1, said top being of transparent material, said inner marginal portion and the final flange of said rear sheet being of opaque material.

3. In a device, as set forth in claim 1, said inner marginal portion and the final flange of said rear sheet being of opaque material, said top being of stiff but resilient flexible and transparent material.

4. In a device, as set forth in claim 1, a horizontal row of stitches provided between the tops 20 of the inner vertical folds of the folds in the back and the top of the downward flange of the upper sheet folded therebetween.

5. A binder or cover for books, magazines, loose leaf sheets and the like, comprising, in combination, a rear sheet having a flexible inner marginal portion, upwardly standing folds formed from said inner margin thereof, offering an upward opening therebetween, a top sheet for the device, the inner marginal portion thereof being folded downwardly and inserted into said upward opening in the folds of the rear sheet, and means to secure together the vertical folds thus formed of the rear and the top thereby forming the back of the device.

6. In a device, as set forth in claim 5, said top being of transparent material.

7. In a device, as set forth in claim 5, said top being of transparent material, said inner marginal portion and the folds of said rear sheet being of opaque material.

WILLIAM HEMPEL.
